UNITED STATES PATENT OFFICE.

JACOB E. NEAHR, OF HARTSDALE, NEW YORK.

MATCH SAFE.

Application filed May 16, 1923. Serial No. 639,300.

This invention relates to combined match-safes and ash-receivers, in which the matches are placed in an open-top receptacle that is contained within a bowl or box which 5 constitutes the ash-receiver.

According to the present improvements, the ash-receiver, which may be in the form of a box, of either metal or porcelain, glass or ceramic ware, is provided with a movable 10 cover, having at one end an open-top match-safe which hangs within the ash-receiver from the cover or lid of the box, and having at the other end a receptacle for slips of match-striking material.

15 Means may be also provided whereby the cover may be employed for extinguishing a cigar.

The cover may be made of either sheet-metal or ceramic or molded ware. If the 20 latter, it may be made in a single piece; but, if made of metal, it is preferably in the form of two lids hinged together at the middle of the ash-receiver, one lid carrying the matches, and the other lid having the 25 pocket for the match-striking slips.

The lid has an aperture down into which is set the match-safe, the latter having a top brim or flange which affords a hanging support for the match-safe upon the lid. 30 This safe serves for long parlor matches, which are thus readily accessible from the top of the contrivance. This parlor-match-safe may be removed, and then short safety matches, contained in the usual small 35 paper open-top box, may be inserted. This paper box is inserted into a frame that is provided upon the under side of the cover, so as to be readily accessible through the top of the cover when the same is closed.

40 At its opposite end, the ash-receiver may be provided with an internal support, upon which to place the lighted end of a cigar, to permit the same to be pinched between the descending cover and the support to extinguish the cigar.

45 Other features and advantages will hereinafter appear.

In the accompanying drawings,

Figure 1 is a plan, and Figure 2 a sectional longitudinal elevation, of a combined match-safe, ash-receiver and match-striker embodying in one form the present improvements.

50 Figure 3 shows a sliding tray to receive a leaf of match-striking material.

Figure 3^a is a combined floor and partition.

Figure 4 illustrates the manner of tearing the match-striking side from a box of 60 safety matches.

Figure 5 is a perspective view of an open-ended and open-bottom shelf or frame provided in the match-safe for receiving an open open box of safety matches; this frame being secured to the under side of the cover 65 of the match-safe.

Figure 6 is a perspective view of the match-safe, showing both ends of the two-part cover lifted and the box of safety matches partly drawn out, and also showing a match-striking slip partly drawn out, and also a cigarette butt in position to be 70 extinguished.

Figure 7 is a perspective view illustrating the manner of extinguishing a cigarette. 75

Figure 8 is a perspective view showing one end of the match-safe and ash-receiver, with the match-safe lifted therefrom, this being the safe which is designed to contain 80 long parlor matches, and being removable to permit the introduction of a common paper box of safety matches, as at Figure 6.

Figure 8^a is a sectional elevation of another embodiment of certain improvements. 85

Figure 9 is a plan, and Figure 10 a sectional longitudinal elevation, of one way of constructing the invention from vitreous or ceramic ware or the like; the cover being made all in one piece and liftable at either 90 end.

Figure 11 is a plan of the metal plate or frame which is attached to the under side of the cover seen at Figures 9 and 10; this plate having provision for taking care of 95 the matches and the match-striking slips or tablets.

Referring more particularly to Figures 1 to 8, inclusive, the ash-receiver comprises a base 20, ends 21, 22, and a top or cover comprising leaves or lids 23, 24, hinged to each other or to the top of the ash-receiver at 25, so that either leaf or lid may be swung up independently of the other, as at Figure 6. 100

At Figures 1 and 2, the long parlor matches 26 stand on the bottom 27 of a sheet-metal match safe or box 28, which may be of rectangular form and pendent from the section or lid 24; said match-box having at its top 105 a rectangular supporting brim or flange 29, 110

to overhang the edges of a rectangular opening 30 in the lid 24, Figure 6. This box may be divided into two chambers by a partition 31, and the safe may be lifted out when it is desired to substitute a box of safety matches. The safety matches may remain in the usual paper box 32 in which they are commonly marketed. This paper box may be slidden endwise into a receiver, the latter being in the form of a frame or slideway which is fixed to and pendent from the under side of the cover 24, and comprises an open bottom 33, sides 34 and a closed end 35, the other end being open for the introduction of the match-box 32. It is only necessary to lift the lid 24 and insert the sliding match-box 32 into the open-ended frame 33, 34, 35, whereupon the matches become accessible through the opening 30 in the cover 24, and the cover may be closed; the side wall 36 of the ash-receiver retaining the box 32 in place when the cover is down. The opposite side wall of the ash-receiver is marked 37. It will be seen that, by providing an opening 38 in the bottom 33 of said frame, it becomes practicable, after withdrawing the match-box 32, to drop the metal match-box 28 through said opening 38, which also serves to steady the match-box 28 against swinging. Thus either kind of matches may be rendered accessible through the opening 30 in the cover 24, and one kind of match-box may be readily substituted for the other, thus effecting economy of room, and making it practicable to supply the demand for long or short match-receptacles by a single kind of receiver, thus enabling business to be carried on with a reduced stock of ash-receivers.

In the center of the cover is a large opening 39 into which may be dropped burnt matches, ashes and refuse.

The opening 39 may be formed at the adjoining edges of the lids, partly in one lid and partly in the other.

In the leaf or lid 23 is provided, at its left-hand end, an oblong opening 40, beneath which is placed a slip 41 of igniting material, which may be of coarse emery paper for use with the parlor matches 26, or of chemically-prepared ignition material for use with the safety matches 42. One or more of these may be slipped into a pocket or receiver comprising a bottom 43, sides 44 and a closed end 45, Figure 3, which is secured to the under side of lid 23 beneath said opening 40. The lid 23 may be raised and one or more slips 41 may be introduced into the open end of the pocket, and then the lid may be dropped. The side of the ash-receiver 36 then confines the slips against dropping from the open end of the pocket. This part is soldered or otherwise secured to the under side of the lid 23. The slips 41 may be torn from the side of the casing 46, in which the short safety-match box 32 is usually marketed, as illustrated at

Figure 4, two of said slips 41 being usually comprised in each box of safety matches 32.

To extinguish a cigar, it may be laid upon a shelf or block 47 fixed to the end 22 of the ash-receiver beneath the bottom 43 of the pocket, Figure 2. In the end 22 of the ash-receiver is formed a cutaway 48, permitting the cigar to be laid upon the block 47, so that the lid 23 may be swung down upon the cigar to pinch and extinguish the same between the lid and the block. Said block 47 may serve as a cigar-rest when the lid is raised.

Thus by a simple, easily operated, inexpensive and attractive construction, provision may be made to hold a variety of matches and a variety of match-striking strips, to take care of ashes and refuse, and to extinguish the cigars.

Referring now more particularly to the device seen at Figures 9 to 11, the ash-receiver may have the same general form as seen at Figure 6, but, instead of metal, it may be formed of vitreous, ceramic or other plastic ware 49; and a cigar-extinguishing block 50 may be molded integral therewith. Around the top of the box may be molded or formed an upwardly-extending flaring brim 51, forming a seat in which is deposited the removable cover or lid 52, also made of molded material and having a central opening 53 for burnt matches, etc. This cover may also have at one end an opening 54 corresponding with 30, and at its other end an opening 55 corresponding with 40.

A bracket 33, 34, 35 may be soldered or otherwise secured to the bottom of a metal plate or frame 55^a, which is secured by rivets 56 to the under side of the ceramic lid 52; the latter having a depression 57 around the border of opening 54, to receive the supporting brim or flange 29 of the metal match-box 28, which is removable to permit the substitution of the sliding safety match-box 32 in the manner already explained in connection with Figure 6. The ceramic lid 52, however, may be swung up from either its right-hand end, as in dotted lines at Figure 10, to permit the introduction of the ignition strips, or from its left-hand end to permit the introduction and withdrawal of the match-box 32.

A pocket or receptacle 58 for the ignition strips may be formed by bending down the metal of the frame or plate 55^a, the pocket or receptacle being closed at one end and open at the other, for reasons already explained. At each end the ceramic lid may have an ear 59 to form a finger-piece for lifting the lid at that end.

At Figure 8^a the ash-receiver is provided at one end with a top 60 permanently fixed thereto; a lid 61 being hinged to the top at 62 and preferably extending for the major portion of the length of the ash-receiver and containing the entire opening 39. The match-holder or safe 63 may be set down

through the top 60 of the receiver and permanently secured thereto. The matches may rest upon a floor 64, the safe being divided by a partition 65 which may be raised when 5 it is desired to accommodate short matches 42 in the safe.

Upon the support 47 is placed a pipe-cleaner, comprising a twisted sheet-metal tongue or leaf 66, having a sheet-metal shank 67, which covers the top of the cigar-extinguisher 47. This tongue 66 may conform to the interior of the bowl 68 of a pipe, so that, by raising the lid 61 and inserting the pipe as illustrated, and turning 15 or rocking the same back and forth, the ashes therein may be loosened, and then the pipe may be knocked upon the post 47 to clear it.

Variations may be resorted to within the 20 scope of the invention, and portions of the improvements may be used without others.

Having thus described my invention, I claim:

1. An ash-receiver provided with a movable cover comprising two lids hinged together midway of the cover, an open-top match-safe hanging from one of said lids within the ash-receiver, and a receptacle upon the other of said lids for a match-striking slip. •

2. An ash-receiver provided with a movable cover, and an open frame or support pendent from said cover and permanently secured thereto and fitted to receive an ordinary paper-box of safety matches inserted endwise into said frame, whereby, when the cover is closed, the box of safety matches is confined in the frame by means of the side wall of the ash-receiver.

3. An ash-receiver provided with a movable cover, an open-top match-safe hanging from said cover within the ash-receiver, and an open frame or support pendent from said cover and permanently secured thereto and fitted to receive an ordinary paper-box of safety matches inserted endwise into said frame, whereby, when the cover is closed, the box of safety matches is confined in the frame by means of the side wall of the ash-receiver, said frame having an open bottom

to permit the pendent match-safe to extend down therethrough.

4. An ash-receiver provided with a movable cover, an open-top match-safe hanging from said cover within the ash-receiver, and a receptacle at one end of said cover for a match-striking slip, an opening being provided in said cover between the match-safe and the match-striking slip, through which matches may be dropped into the ash-receiver. 60

5. An ash-receiver provided with a movable cover, and an open frame pendent from said cover and permanently secured thereto, an ordinary paper-box of safety matches 65 inserted endwise into and fitting to said frame, whereby, when the cover is closed, the box of safety matches is confined in the frame by means of the side wall of the ash-receiver, said frame comprising a bottom 70 having a large opening and also comprising sides and a closed end, the other end being open for the introduction of the paper match-box; said open frame serving to steady the pendent match-box against swinging. 75

6. An ash-receiver providing with a movable cover, said cover having provision for holding either a deep match-box to contain long safety matches in standing positions, 80 or an ordinary small paper safety match-box to contain short safety matches; the matches in either case being accessible through an opening in the top of the cover.

7. An ash-receiver provided with a movable cover, said cover having provision for holding either a deep match-box to contain long safety matches in standing positions, or an ordinary small paper safety match-box to contain short safety matches; the matches 90 in either case being accessible through an opening in the top of the cover, said cover having at one end another opening, and a receptacle beneath the last opening to form a pocket to receive a slip of igniting material; said pocket having an open end for the insertion of the slip, and the side wall of the ash-receiver confining the slip within the pocket when the cover is down in place. 95

JACOB E. NEAHR.
